UNITED STATES PATENT OFFICE.

PHILIPP FUNCK, OF ROCHESTER, NEW YORK, ASSIGNOR TO JOHNSON & LUND, OF PHILADELPHIA, PENNSYLVANIA.

VULCANIZER.

SPECIFICATION forming part of Letters Patent No. 662,281, dated November 20, 1900.

Application filed April 13, 1900. Serial No. 12,734. (No model.)

To all whom it may concern:

Be it known that I, PHILIPP FUNCK, of Rochester, in the county of Monroe and State of New York, have invented certain new and 5 useful Improvements in Vulcanizers; and I do hereby declare the following to be a full, clear, and exact description of the same, reference being had to the accompanying drawings, forming a part of this specification, and 10 to the reference-numerals marked thereon.

My present invention has for one object to provide a simple and improved closure for vulcanizers or similar vessels that is capable of being operated quickly by a single movement of a handle or operating part to close 15 the receptacle and form a tight joint between the retort and the cover therefor, and has for its further object to provide a means of support for the latter whereby it may be turned 20 to one side to allow free access to the retort and also easily adjusted to take up wear between the parts.

To these and other ends my invention consists in certain improvements in construction 25 and combination of parts, all as will be described, and the novel features pointed out in the claims at the end of this specification.

In the drawings, Figure 1 is a vertical sectional view of a vulcanizer constructed in accordance with my invention. Fig. 2 is a similar view taken on the line 22 of Fig. 1. Fig. 3 is a horizontal sectional view on the line 33 of Fig. 2. Fig. 4 is a similar view on the line 44 of Fig. 2, and Fig. 5 is a side elevation of 35 the cam-ring.

Similar reference-numerals in the several figures indicate similar parts.

1 indicates the base or support, preferably circular in form, upon which rests the retort-frame 2, secured by screws 3 passing through 40 the support and engaging lugs 4 on the lower side of the frame.

5 indicates a yoke-frame extending above the retort 6 and adapted to be turned to the 45 side, having a shoulder 7 upon one end bearing upon a lug or projection 8 and a pin 9 extending vertically through the latter and provided with a nut 10, which secures the yoke on the frame. The opposite end of the yoke 50 is provided with a lip or hook 11, adapted to engage beneath a pin 12 when the yoke is in

the normal position to prevent its upward movement and hold it rigid upon the frame when pressure is applied to lock the cover on the retort. A handle 13 is applied to the free 55 end of the yoke, forming a convenient means for operating it laterally. The cover or closure 14 is adapted to be held stationary relative to the retort 6, and the latter is adjusted vertically to close the parts, and in order that the 60 said adjustment may be limited or any wear between the parts compensated for I attach the cover to the yoke by means of an adjusting-screw 16, having its lower end shouldered and bearing against the bottom of a central recess 65 in the former. The cover is attached to the screw and permitted a free rotary movement thereon by means of a pin 17, passed through one side of the recess and engaging in an annular groove 18, formed near the end of the 70 screw. A collar 19, having a milled edge, serves to adjust the screw to raise or lower the cover 14, and a set-screw 20 locks it in the desired position.

21 indicates a suitable packing-ring arranged 75 between the lower side of the cover and the upper edge of the retort, making a steam-tight joint.

The retort is arranged centrally within the casing, and beneath the cover and about its 80 upper edge is a flange or ring forming a shoulder 22 upon the exterior of the retort and upon which the latter is supported on a vertically-movable ring 23, adjustably mounted in the frame 2, but prevented from rotary movement and removal therefrom by screws 24. The vertical movement of the ring is accomplished by means of a revoluble collar 25, located below the latter, having the inclined or spiral way upon its lower side co-operating 85 with a similar surface 26, formed upon a stationary ring 27, held upon a step or rim 28, formed at the bottom of the frame, to which it is secured by a screw 29. Grooves 30 are formed in the upper and lower edges of the 90 movable collar and in the proximate faces of the rings 23 and 27, and arranged therein are balls 31 to reduce the friction between the parts and permit their easy operation. The grooves formed in the cam-surfaces are not 95 continuous owing to the difference in elevation between their opposite ends, and between

these surfaces I arrange only a sufficient number of balls in the grooves to permit their lineal movement as the collar is rotated, a screw or pin 32 being provided at the end of 5 the groove to limit their upward movement, and a similar pin 33 at the opposite end arrests the downward travel. This arrangement allows the balls to roll along the grooves in the direction of the moving part, reducing 10 the friction to a minimum. An operating-handle 34, mounted upon a pin 35, operating through an aperture 36 in the frame and threaded into the collar, provides a simple means for operating the latter, and the length 15 of the aperture can be arranged, if desired, to limit its movement.

A short pipe 40, communicating with the interior of the vessel, is provided in the cover 14, upon which may be mounted any suitable 20 gage for registering the steam-pressure, and by mounting the cover upon the yoke and arranging the parts to move bodily out of line with the retort I obviate the inconvenience in handling the latter when the gage is connected directly thereto, and by so mounting 25 it the parts are always in a convenient position for use and not liable to injury by unnecessary handling.

The operation of the device will now be 30 readily understood. The collar 25 is revolved to its lowermost position on the spiral cam-way on the ring 27 and the retort 6 is suspended on the ring 23. The yoke 5 is now moved into position, with its hook 11 beneath the pin 35 12, and the cover is adjusted loosely above the retort by means of the screw 16, allowing the free lateral movement of the yoke, and the set-screw 20 prevents the accidental movement of the cover, and its subsequent adjustment 40 is only necessary to take up the wear between the parts. The collar 25 is then revolved by means of the handle 34 in the direction indicated by the arrow in Fig. 4, when the coöperating cam-surfaces will elevate the 45 ring 23, carrying with it the retort, the upper edge of which will engage the packing-ring 21, forming a tight joint between the parts.

Vulcanizers constructed according to my 50 invention are simple and effective in their operation, and by arranging the balls between the bearing-surfaces and employing the long cam-surfaces the retort and closure therefor can be held tightly together and be very easily applied and adjusted.

55 I claim as my invention—

1. In a vulcanizer, the combination with the retort having the flange, the frame surrounding the retort, having a cam-surface, and the cover connected to the frame and held stationary above the retort, of the clamping-collar extending loosely around the retort beneath the flange and capable of rotation independently thereof, and having a cam-surface coöperating with the corresponding 65 surface on the frame to move the retort and cover relatively.

2. In a vulcanizer, the combination with the

retort, the frame surrounding the latter, the yoke pivoted thereon movable to the side and the cover secured to the latter, of the collar 70 surrounding the retort having the cam-surface coöperating with a similar surface on the frame, a ring separate from the retort interposed between the collar and the retort for supporting the latter and operating devices 75 for revolving the collar in either direction to engage and disengage the cover and retort.

3. In a vulcanizer, the combination with a retort having the outwardly-extending projection upon its upper end, the frame surrounding the retort having the cam-surface, and the pivoted yoke mounted upon the frame and swinging to the side thereof, of the cover 80 adjustably mounted on the yoke, the collar supporting the retort having the cam-surface 85 coöperating with the similar surface on the frame and means for rotating the collar in either direction to cause the engagement or disengagement of the cover and retort.

4. In a vulcanizer, the combination with 90 an annular frame having the cam-surface, the collar lying within the frame having the cam-surface coöperating therewith, the yoke pivoted on the frame and the cover mounted on the yoke, of the retort having the flange 95 supporting it on the collar and means for revolving the collar to elevate the retort and cause its engagement with the cover.

5. In a vulcanizer, the combination with a frame having an annular shoulder upon its 100 inner side provided with a cam-surface, a collar rotatable in the frame having the cam-surface, and balls provided between the said surfaces, of a retort having the flange upon its exterior whereby it is supported on the 105 collar, a yoke having a cover thereon and means for operating the collar to cause the engagement of the retort with the cover.

6. In a vulcanizer, the combination with a 110 supporting-frame, having the annular flange upon its inner side, the ring supported on the flange having the cam-surface provided with the groove, the collar having the cam-surface upon its lower side provided with the groove and the balls arranged in the grooves between 115 the said surfaces, of the retort supported on the collar, the yoke pivotally mounted on the frame, the cover carried on the yoke and a handle connected to the collar and extending to the exterior of the frame for operating the 120 former to cause the engagement of the retort with the cover.

7. In a vulcanizer, the combination with a supporting-frame, the annular flange upon its inner side having the cam-surface thereon, 125 the collar having the cam-surface coöperating therewith, the vertically-movable ring located above the collar and secured against rotation, and the retort supported on the ring, of the pivoted yoke on the frame, the cover 130 mounted on the yoke, and a handle on the collar for operating the latter in either direction to cause the engagement and disengagement of the retort and cover.

8. In a vulcanizer the combination with a supporting-frame, the annular flange secured upon the inner side thereof having the cam-surface, the collar having the cam-surface 5 upon its lower side coöperating therewith and provided with the groove upon its upper surface, the vertically-movable ring located above the collar having the groove, balls arranged in the grooves between the collar and ring 10 and the retort supported on the ring, of the yoke pivoted to the frame, the cover thereon and a handle attached to the collar.

9. In a vulcanizer, the combination with a supporting-frame having the ring secured 15 upon the inner side thereof having the cam-surface provided with the groove, the collar having the grooved cam-surface upon its lower side coöperating therewith and having the groove in its upper surface, the vertically- 20 movable ring arranged above the collar having the groove, balls arranged in the grooves between the cam-surfaces and between the collar and rings, and the retort supported on

the latter, of the yoke pivoted to the frame, the cover thereon adjustable relative to the 25 frame and a handle on the collar for rotating the latter to elevate the retort into engagement with the cover.

10. In a vulcanizer, the combination with a supporting-frame having the cam-surface, 30 the collar arranged therein provided with the cam-surface, the vertically-movable ring arranged above the collar and the retort supported on the ring, of the yoke extending above the retort pivoted at one end to the 35 frame and movable to the side thereof, the hook upon the opposite extremity engaging beneath a projection on the frame, the cover, an adjusting-screw, the yoke having the shoulder engaging in a recess in the cover and 40 loosely connected, and an operating-handle attached to the collar.
